CLUTCH MECHANISM

William A. Smith, Sr., Athens, Pa., assignor to
 Ingersoll-Rand Company, Jersey City, N. J., a
 corporation of New Jersey

Application June 16, 1937, Serial No. 148,473

1 Claim. (Cl. 192—87)

This invention relates to rock drills, and more particularly to a clutch mechanism for rock drills embodying rotation mechanism for shifting the working implement and feeding mechanism for actuating the rock drill relatively to its support.

One object of the invention is to enable the clutch to be actuated quickly and positively into the engaging and releasing positions.

Other objects will be in part obvious and in part pointed out hereinafter.

In the drawings accompanying this specification and in which similar reference numerals refer to similar parts,

Figure 1 is a longitudinal view, partly in section, of a rock drilling mechanism constructed in accordance with the practice of the invention.

Figures 2 and 3 are transverse views taken through Figure 1 on the lines 2—2 and 3—3, respectively.

Figure 4 is a transverse view taken through Figure 3 on the line 4—4.

Figure 5 is an enlarged view, similar to Figure 1, showing the driving and reversing devices for the feeding apparatus of the rock drill,

Figure 6 is a transverse view taken through Figure 1 on the line 6—6, and

Figure 7 is a plan view in section, taken through Figure 1 on the line 7—7.

Referring more particularly to the drawings, 20 designates a rock drilling mechanism comprising a rock drill 21 and a shell 22 to guide the rock drill and accordingly has a pair of guideways 23 to slidably receive ribs 24 carried by the casing parts of the rock drill 21.

The rock drill 21 comprises the usual cylinder 25 having a piston chamber 26 to accommodate a reciprocating hammer piston 27 which controls a free exhaust port 28 and has a reduced cylindrical stem 29 to deliver blows against a hollow working implement 30 for actuating it into the work.

The peripheral surface of the stem 29 is unbroken and the stem is guided by a closure 31 inserted into the front end of the cylinder 25. The closure 31 has an external flange 32 which abuts the front end of the cylinder 25 and serves as a seat for an end of a front head 33 containing rotary chuck mechanism 34 which interlockingly engages the working implement 30, in a well known manner, to prevent relative rotary movement between the two.

The chuck mechanism 34 preferably comprises a chuck 35 which bears directly against the inner surface of the front head 33 and contains a bush-

ing 36 which, in the arrangement shown, is the chuck element that interlockingly engages the working implement.

In the rearward end of the cylinder 25 is an enlarged recess 37 to accommodate valve mechanism 38 of which only the chest is shown. The valve mechanism may be of any well known type and the rock drill may be provided with the usual ports and passages (not shown) controlled by the valve mechanism to distribute pressure fluid to the ends of the piston chamber for actuating the piston 27.

The recess 37 also contains a uni-directional rotary motor 39 shown as being of the vane type and comprising a casing 40 which may be affixed to the cylinder 25 in any convenient manner. The casing 40 is bored to provide a piston chamber 41 wherein is arranged a rotor 42 carrying the vanes 43 against which pressure fluid acts for driving the rotor. The pressure fluid employed for this purpose is conveyed to the chamber 41 by a passage 44 in the casing 40 and ports 45 affording communication between the passage 44 and the chamber 41. The exhaust fluid may pass from the chamber 41 through an exhaust port 46 in the casing 40 and the cylinder 25. Preferably the passage 44 is extended to the valve mechanism to also convey thereto the pressure fluid employed for actuating the hammer piston 27.

The rotor 42 is mounted upon and keyed to a shaft 47 extending beyond the ends of the casing 40 and into anti-friction bearings 48 carried by plates 49 and 50 forming closures for the front and rear ends of the chamber 41, respectively.

In addition to the functions stated the plate 50 also serves as a seat for a back head 51 forming the rearmost casing part of the rock drill and which may be secured to the cylinder 25 by side rods 52, as may also be the front head 33.

In accordance with the practice of the invention the motor 39 serves to impart rotary movement to the chuck mechanism 34 and also to effect advancing and retractive movement of the rock drill with respect to the shell 22. The shaft 47 of the motor accordingly carries a pinion 53 which meshes with a gear 54 of a transmission shaft 55 mounted in anti-friction bearings 56 and 57 seated in the plate 50 and the back head 51, respectively. Intermediate the gear 54 and the bearing 57 is a pinion 58 which, like the gear 54, may be an integral part of the shaft 55 and meshes with a gear 59 carried by a shaft 60 extending longitudinally of the rock drill and carrying, at its front end, a pinion 61 which meshes

with a gear 62 on the periphery of the chuck 35. The power employed for effecting actuation of the rock drill relatively to the shell 22 is also transmitted through the shaft 55 which, accordingly, has a pinion 63 rearwardly of the bearing 57 and extending into a chamber 64 in the back head 51. The chamber 64 preferably lies coaxially with the piston chamber 26 and contains a pair of driving members 65 and 66 which are supported by a stationary shaft 67 mounted in the back head 51.

The driving members 65 and 66 are freely rotatable with respect to each other and with respect to the shaft 67. As a preferred form of construction the driving member 66 is clamped, as by means of a nut 68, to a sleeve 69 disposed rotatably upon the shaft 67 and carrying at its opposite end a gear 70 which meshes with the pinion 63, and on the periphery of the sleeve 69, adjacent the gear 70, is an anti-friction bearing 71 upon which is mounted the driving member 65.

The driving member 65 lies on one side of the anti-friction bearing 71 to confront the driving member 66. It has a skirt 72 containing the anti-friction bearing 71 and extends into the same transverse plane as the gear 70, and on the inner surface of the skirt 72 are gear teeth 73 which mesh constantly with the pinion 63. An additional bearing surface is provided for the driving member 65 by an integral sleeve 74 encircling the portion of the sleeve 69 lying between the driving members 65 and 66.

Mounted upon the sleeve 74, and whereon it is freely rotatable, is an idler sprocket 75 which is capable of a slight degree of movement longitudinally of the sleeve 74 and engages a chain 76 which is also trained over sprocket teeth 77 carried by a feed nut 78. The feed nut is journaled in a lug 79 on the back head 51. It is freely rotatable in the lug 79 and is in threaded engagement with a feed screw 80 extending therethrough and longitudinally of the shell 22 whereby it is supported.

Normally, the feed screw 80 remains stationary and may be held thus by a latch 81 having a detent 82 to engage notches 83 in a flange 84 near the rear end of the feed screw. The latch is maintained in locking engagement with the feed screw by a spring 85, and on the rearward extremity of the feed screw is the usual crank 86 whereby the feed screw may be manually rotated if desired.

In the confronting portions of the driving members 65 and 66 are piston chambers 87 and 88, respectively, to receive pistons 89 and 90 carried by the sprocket 75 and to which they may be affixed in any suitable manner. The outermost portions of the pistons 89 and 90 constitute friction surfaces 91 adapted to engage friction disks 92 arranged in the bottoms of the piston chambers 87 and 88.

To the end that the sprocket wheel may be conveniently actuated into and held in frictional engagement with the friction disks 92 to cause the sprocket wheel and, therefore, the feed nut 78 to be rotated in one direction or the other by either the driving member 65 or the member 66, depending upon the direction in which it is desired to actuate the rock drill relatively to the shell, the ends of the pistons 89 and 90 adjacent the friction disks 92 constitute pressure surfaces 93 and 94, respectively, which are selectively subjected to pressure fluid for shifting the sprocket wheel 75. The pressure fluid employed for this purpose is valved to the piston chambers 87 and

88 by a manually operable valve 95 in the back head 51.

The valve 95 is of the rotary type, having a central chamber 96 which is in constant communication with the pressure fluid supply conduit 97 through a passage 98 in the back head. In the wall of the valve 95 is a pair of ports 99 and 100 which are spaced along the length of the valve 95 and arranged angularly with respect to each other. Thus, in one position of the valve 95 the port 100 registers with a supply passage 101 extending through the back head, the shaft 67 and the sleeves 69 and 74 and opening into the piston chamber 87, and in another position of the valve 95 the port 100 is blanked off and the port 99 registers with a supply passage 102 arranged in the same elements as the passage 101 and opening into the piston chamber 88.

In the portion of the back head 51 encasing the valve 95 is a pair of exhaust ports 107 and 108 which may respectively be communicated with the passages 101 and 102 by partly-annular grooves 109 and 110 in the periphery of the valve 95. The grooves 109 and 110 are so arranged that they may be placed either singly or simultaneously in communication with the ports which they control. That is to say, when the valve 95 is in position to admit pressure fluid into the passage 101 the groove 110 will establish communication between the passage 102 and the exhaust port 108. Similarly, when the port 99 is in registry with the passage 102 the groove 109 will be in position to effect communication between the passage 101 and the exhaust port 107. The grooves 109 and 110 are, moreover, so proportioned that they have portions lying in the same longitudinal plane. Thus, the valve may be positioned to vent both piston chambers 87 and 88 to the atmosphere.

The valve 95 is located in the back head and preferably adjacent the main throttle valve 103 whereby the admission of pressure fluid from the supply conduit 97 to the motor 39 and the valve mechanism 38 is controlled. The back head 51, moreover, serves as a housing for a rotary valve 104 which controls the admission of cleansing liquid to a water tube 105 extending coaxially through the rock drill for supplying cleansing fluid to the working implement to flush the cuttings from the hole being drilled. The water tube 105 may be of a well known type and is secured in position by a plug 106 threaded into the rearmost end of the back head 51.

As a first step in the operation of the device, and assuming that it be intended to move the rock drill toward the work to actuate the working implement 30 thereto, the throttle valve 103 is opened to admit pressure fluid to the passage 44 and thus to the motor 39 and the valve mechanism 38. The valve mechanism 38 will then operate to distribute pressure fluid to the ends of the piston chamber 26 for actuating the piston 27 against the working implement 30. At the same time the motor 39 is set in operation and its movement is transmitted through the transmission shaft 55 and the shaft 60 to the chuck mechanism 34 for shifting the cutting bit (not shown) of the working implement 30 to new positions between the blows of the hammer piston.

Simultaneously with or immediately following the starting of the motor 39 and the percussive element of the drill the valve 95 is rotated to the position shown in Figures 5 and 7 in which the port 100 registers with the supply passage 101. Pressure fluid then flows through these channels 75

into the piston chamber 87 and, acting against the pressure surface 93 of the piston 89, shifts the sprocket 75 rearwardly and presses the pressure surface 94 into frictional engagement with the adjacent friction disk 92 carried by the driving member 66. The sprocket 75 is held in frictional engagement with the driving member 66 by the pressure fluid acting against the piston 89 and will rotate with the driving member 66.

10 The rotary movement of the sprocket 75 is transmitted by the chain 76 to the feed nut 78 which will then be rotated relatively to the feed screw so that the rock drill 21 will be gradually advanced along the shell 22 toward the work in accordance with the degree of penetration of the working implement thereto. In this way the percussive element of the rock drill will be constantly maintained in the correct operative relationship with the working implement.

15 After the working implement 30 has penetrated the work to the limit of its extent the valve 95 is rotated to a position in which the port 100 is moved out of registry with the passage 101 and the port 99 registers with the passage 102. Pressure fluid is then admitted into the piston chamber 88 and acts against the pressure surface 94 to shift the sprocket 75 forwardly and press the pressure surface 93 against the adjacent friction disk 92. Inasmuch as the driving member 65 rotates in a direction opposite to that of the driving member 66 the direction of rotation of the sprocket 75 will be reversed as will also be that of the feed nut 78. Thus, during the subsequent operation of the motor 39 the movement of the feed nut will cause the rock drill to be moved rearwardly along the shell 22 to its starting position.

20 Whenever it is desired to impart only slight advancing or retracting movement to the rock drill the valve 95 may be rotated to admit only a small amount of pressure fluid into the piston chambers 87 or 88. Such pressure fluid will press the sprocket 75 only lightly against a friction disk so that there may be a degree of slippage

25

between the friction disk and the sprocket. In consequence, the feed nut will be rotated slowly and the movement of the rock drill relatively to the shell will be correspondingly slow. In the event that it be desired to discontinue movement of the rock drill with respect to the shell the valve 95 is shifted to a neutral position in which both piston chambers 87 and 88 are cut off from the source of pressure fluid supply. The sprocket 75 may then assume a neutral position and will 10 be unaffected by the movement of the adjacent rotary parts.

Normally, the feed screw 80 will remain stationary and will be held thus by the latch 81. There may be occasions, however, when it may 15 be desirable or advantageous to shift the rock drill along the shell without operating the rotary and percussive elements. In such event the latch 81 may be released from the notches 83 and the feed screw may be then rotated by means of the 20 crank 86. Similarly, when the rotary motor 39 is operating and it may be desired to momentarily nullify, wholly or in part, its feeding movement the feed screw may be rotated in a direction opposite to that in which the feed nut rotates, 25 either fast or slowly depending upon the feeding movement required. In like manner, the feed screw may be rotated in the same direction as the feed nut to expedite the movement of the rock drill along the shell.

30 I claim:

Clutch mechanism, comprising a pair of driving members rotating in opposite directions and each member having a piston chamber, a driven member having pistons extending slidably into 35 the piston chambers and forming closures therefor, pressure surfaces on the pistons, friction members in the piston chambers carried by the driving members, and means for selectively subjecting a pressure surface to pressure fluid to 40 press the other pressure surface into engagement with a friction member.

WILLIAM A. SMITH, SR.
